GIBSON GROVES, OF PARRY SOUND, ONTARIO, CANADA.

FIRE-ALARM SYSTEM.

1,185,306.

Specification of Letters Patent.

Patented May 30, 1916.

Application filed August 31, 1915. Serial No. 48,372.

To all whom it may concern:

Be it known that I, GIBSON GROVES, of the town of Parry Sound, in the district of Parry Sound, Province of Ontario, Canada, 5 a subject of the King of Great Britain, have invented certain new and useful Improvements in Fire-Alarm Systems, of which the following is a specification.

This invention relates to fire alarm systems particularly adapted for small places where it is necessary to summon members of the brigade from their residences in case of fire, and my object is to devise a system in which the sounding of an alarm from any 15 particular box gives an alarm at the fire hall and also at the nearest fireman's residence, said system being adapted to be conditioned to then enable an alarm to be sent through all the circuits to all firemen needed to 20 answer the call.

A further object is to arrange the system so that any circuit which may accidentally become broken may be cut out and so that the system may be tested at any time without sounding an alarm.

I attain my objects by means of the constructions hereinafter described and illustrated in the accompanying drawings in which—

30 Figure 1 is a diagrammatical view of the system with the selector switch in its normal position; and Fig. 2 a diagrammatical view of the selector switch in the position it assumes when an alarm is being sent out 35 from the central station to the firemen's residences.

In the drawings like numerals of reference indicate corresponding parts in the different figures.

40 Referring to Fig. 1, it will be seen that a plurality of alarm circuits 1 are provided. Each circuit includes a magneto 2 suitably located for the sending in of an alarm and usually also a bell or other alarm device 3 45 located in a fireman's residence or other suitable location. Each circuit also includes an indicator 4 preferably of the usual drop type and located at a central station.

Each circuit 1 has its ends connected at 50 the central station with pairs of contacts 5—6 on a selector switch 7. This selector switch is provided with the rotary member 8 which is adapted to complete a circuit between each pair of contacts 5—6 as shown 55 in Fig. 1.

9 is a hand lever, by means of which the switch may be operated.

It will be seen that normally each alarm circuit 1 is closed so that on the ringing of an alarm by the operation of the magneto in 60 any circuit the indicator in that circuit is operated and also the alarm device in a fireman's residence, or elsewhere outside the central station.

In order that the alarm devices in all the 65 circuits may be simultaneously operated without affecting the indicators at the central station, the following arrangement is provided: Between each pair of contacts 5—6 is located a contact 10 with which is 70 connected a wire 11, so connected with the circuit 1 as to form a cut-out for the indicator 4 therein. When the selector switch is moved to the position shown in Fig. 2, the circuits 1 are still closed, but the indicators 75

are cut out. To one of the contacts 5 and to a contact 10 separated from the contact 5 by one of the contacts 6 is connected the circuit 12 in which is located the magneto 13. When the selector switch is in the position 80

shown in Fig. 2, by actuating the magneto 85 the alarm devices in all the circuits may be simultaneously operated, and by arranging a code of signals each alarm device may be caused to indicate the location of the fire. Simultaneously with the actuation of the indicator it is desirable to sound an audible alarm at the central station. For this purpose the circuit 14 is provided at the central station, which includes the bell 15. This circuit 14 is provided at each indicator with 90 a contact 16 at which the circuit is closed on the drop of the indicator. Such devices are well known in the art and require no detailed description.

95 As the alarm circuits are all in series when the selector switch is in its second position a break in any one circuit will prevent the sending of signals to the rest. Such a break, however, is easily discovered by successively 100 bridging the contacts on the selector switch. As soon as the contacts of the broken circuit are bridged the operation of the magneto sounds the alarm and the broken circuit can be left cut out until repairs can be

105 effected. As the bells are responsive to the alternating current generated by the magneto, any circuit can be tested by direct current at any time without an alarm being sounded.

From the above description it will be seen that I have devised a fire alarm system which will satisfactorily attain the objects of my invention as set out in the preamble 5 to this specification.

What I claim as my invention is:—

1. In a fire alarm system, the combination of a plurality of alarm circuits each including a magneto, an electro-magnetic alarm device 10 vice at an out station and an electro-magnetic indicator at a central station; a selector switch provided with pairs of contacts to which said circuits are connected; a branch in each circuit whereby the indicator in each circuit 15 may be cut out; a contact on the selector switch between each pair of contacts to which said branches are connected; a rotary switch member adapted to connect either the contacts of each pair or one of each pair and 20 the adjacent branch contact; a magneto; and contacts on the selector switch whereby the magneto is put in circuit with the alarm circuits and the alarm circuits in series when the switch is moved to cut out the indicators. 25
2. In a fire alarm system, the combination of a plurality of alarm circuits each includ-

ing a magneto, an electro-magnetic alarm device at an out station and an electro-magnetic indicator at a central station; a selector switch provided with pairs of contacts to 30 which said circuits are connected; a branch in each circuit whereby the indicator in each circuit may be cut out; a contact on the selector switch between each pair of contacts to which said branches are connected; a rotary 35 switch member adapted to connect either the contacts of each pair or one of each pair and the adjacent branch contact; a magneto; contacts on the selector switch whereby the magneto is put in circuit with the alarm circuits and the alarm circuits in series when the switch is moved to cut out the indicators; and an extension bell circuit adapted to be closed by any one indicator. 40

Signed at Parry Sound, this 29th day of 45 July, 1915, in the presence of the two undersigned witnesses.

GIBSON GROVES.
